Patented December 22, 1903.

UNITED STATES PATENT OFFICE.

LEWIS A. BROWN, OF ST. LOUIS, MISSOURI.

DESIGN FOR AN INK-RECEPTACLE.

SPECIFICATION forming part of Design No. 36,694, dated December 22, 1903.

Application filed September 17, 1903. Serial No. 173,624. Term of patent 7 years.

To all whom it may concern:

Be it known that I, LEWIS A. BROWN, a citizen of the United States, and a resident of St. Louis, Missouri, have invented a new, original, and ornamental Design for Ink-Receptacles, of which the following is a specification.

Figure 1 is a perspective view of two of the sides and the top of an ink-receptacle, showing my design; and Fig. 2, a similar view taken from the opposite corner of the ink-receptacle, illustrating the design on the other two sides or faces of the ink-receptacle.

I claim—

The new, original and ornamental design for an ink-receptacle, as herein shown.

In testimony whereof I hereto set my hand, this 14th day of September, 1903, in the presence of two witnesses.

LEWIS A. BROWN.
